UNITED STATES PATENT OFFICE.

CORNELIUS MORTENSEN, OF LOUISVILLE, KENTUCKY.

MILK-TREATING MACHINE.

Application filed April 18, 1924. Serial No. 707,507.

This invention relates to an apparatus especially designed for treating milk, the primary object of the invention being to provide novel means for maintaining milk at the required temperature for a period of time sufficiently to accomplish the Pasteurization thereof.

Another important object of the invention is to provide a revolving body portion having a plurality of containers supported thereby, novel means being employed in connection with the containers for automatically filling and discharging fluid after it has been treated.

15 A still further object of the invention is to provide means to exclude air from the containers while the milk is passing thereto, thereby insuring against the heat of the milk passing off therefrom during the filling 20 of the containers.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without departing from the spirit of the invention.

Referring to the drawings:

Figure 1 is a sectional view taken on line 1—1 of Figure 2.

35 Figure 2 is a plan view of an apparatus constructed in accordance with the invention.

Figure 3 is an elevational view disclosing the receiving tank and valve operating 40 members carried thereby.

Figure 4 is a sectional view taken on line 4—4 of Figure 2, disclosing the guarding caps that guard the upper portions of the partitions between the containers.

45 Referring to the drawings in detail, the reference character 5 designates the base of the machine which is formed with a bearing 6 on which the lower end of the shaft 7 is positioned, which shaft extends upwardly and 50 provides a support for the rotary member 8 that supports the containers or milk receiving tanks.

The rotary member 8 is circular in formation and is mounted on a supporting member 9 that is secured to the shaft 7, there being provided a ring gear 10 on the support-

ing member 9 for purposes to be hereinafter more fully described.

The body portion of the rotary member 8 is indicated at 11 and is in the form of a 60 length of sheet metal having its lower edge secured to the member 8 at 12, the ends being brought together and secured as by soldering. Disposed within the body portion are a plurality of tanks 13 which are supported in spaced relation with the member 8 and in spaced relation with the inner surface of the member 11, the spaces being filled with a suitable insulating material such as 65 layers of cork or the like, to hold the heat 70 of the contents of the tanks.

These tanks 13 also include side walls 14, the side walls of one tank being spaced from the side walls of the adjacent tank providing a space to receive insulating material, 75 insulating one tank from the other to insure against one tank being affected by the temperature of its adjacent tank.

Communicating with each tank 13 is a spigot 15 which is supported as by means of 80 a quick detachable union 16 affording means whereby the spigots may be readily disconnected to facilitate the cleaning thereof.

The passage of fluid through the spigots 15 is controlled by the operating levers 17 85 which are connected with suitable valve members not shown, and as clearly illustrated by Figure 1 of the drawings, these levers 17 are engaged by the cam 18 that lies in the path of travel of the levers 17 as the 90 body portion of the apparatus is revolved.

This cam member 18 is supported at the upper edge of the receiving tank 19 that receives the milk from the containers supported within the body portion, there being provided an upwardly extended finger 20 positioned at the opposite end of the receiving tank 19 that lies in the path of travel of the levers 17 to move the levers to their active or closing positions so that when a lever has 100 been operated to close a valve, the tank is ready for refilling.

As clearly shown by Figure 1 of the drawings, the body portion and tanks 13 are closed by means of the cover 21 which has its 105 outer edge secured to the upper edge of the body portion 11 as at 22. The cover 21 is formed with a circular cut out portion disposed adjacent to the center thereof, which cut out portion is normally closed by the stationary disk-like member 23. This disk-like member supports a trough-like member 24 in 110

which the extensions 25 of the disk 26 are positioned, the disk 26 acting to close the trough-like member 24 and at the same time provide means for supporting the feed pipe 27.

A relatively small opening is formed in the supporting disk 26 to permit the flexible pipe member 27 to be extended therein, which pipe section establishes communication between the tanks 13 and a suitable tank wherein the milk has been heated in Pasteurizing the same, prior to its entrance to the tanks 13. From the foregoing it will be obvious that due to this construction, the upper portions of the tanks are closed at all times and due to the fact that the body portion 11 revolves under the disk-like member 23, it is unnecessary to open or close covers to admit the milk to the tanks making a structure which is absolutely automatic.

Guarding plates indicated at 28 are positioned over the partitioning walls between the tanks 13 at points directly under the pipes 24, so that when the body portion 11 is moved to bring another tank under the flexible pipe 27, the milk passing from the pipe 27 will not enter the space between the walls of the adjacent tanks to deteriorate the cork insulating material to impair the insulating qualities thereof.

Positioned under the body portion 11 is a support 29 on which is mounted a suitable motor indicated at 30, which motor transmits motion through a train of gears which includes a worm 31 meshing with the ring gear 10, the reduction of gearing being such as to cause the body portion 11 to make one complete revolution at a predetermined period, for example every forty minutes to meet the present requirements of Pasteurization.

It might be further stated that the number of tanks employed in the body portion 11, are such as to cause a tank to be filling simultaneously with the discharging of its adjacent tank, while the contents of the remaining tanks are held for a given period of time at a predetermined temperature.

In the operation of the device, the motor 30 is placed in motion and the supply of milk which has been heated to a predetermined degree is admitted to the tank 13 po-

sitioned directly under the flexible pipe 27. The gearing which rotates the body 11 is such as to cause an empty tank to be brought to a receiving position under the pipe 27 when its adjacent tank has been filled, and it follows that as the tanks become filled and reached a point where they may discharge the contents thereof, the fluid has been held at a predetermined temperature for a given time.

I claim:—

1. In an apparatus for treating milk, a body portion, a plurality of tanks supported within the body portion, a cover for the tanks, a disk-like member forming a part of the cover, said cover adapted to move with respect to the disk-like member, a discharge pipe extending through the disk-like member and adapted to supply milk to the tanks, as they are moved under the discharge pipe, means for rotating the body portion, and means for controlling the passage of fluid from the tanks.

2. In an apparatus for treating milk, a body portion, a plurality of tanks supported within the body portion, a cover for the tanks, said cover having a cut out portion, a disk-like member positioned over the cut out portion of the cover, said disk-like member having openings, a trough-like member positioned in the openings, a disk having extensions fitted in the trough-like member, said body portion adapted to move under the last mentioned disk, and a feed pipe extending through the last mentioned disk to supply material to the tanks.

3. In an apparatus for treating milk, a rotatable body portion, a plurality of tanks supported on the body portion, a cover for the tanks, a trough-like member supported by the cover, angularly disposed guarding plates positioned within the trough-like member and adapted to guard the spaces between adjacent tanks, a disk for covering the trough-like members, a feed pipe extending through the disks to supply material to the tank and means for discharging material from the tanks.

In testimony that I claim the foregoing as my own, I have hereto affixed my signature.

CORNELIUS MORTENSEN.
